UNITED STATES PATENT OFFICE.

CHRISTIAN WILHELMSEN, OF GULFPORT, MISSISSIPPI.

JOURNAL-BOX OR ATTACHMENT THEREFOR.

1,033,293.

Specification of Letters Patent. Patented July 23, 1912.

Application filed December 7, 1910. Serial No. 596,154.

To all whom it may concern:

Be it known that I, CHRISTIAN WILHELMSEN, a citizen of the United States, residing at Gulfport, in the county of Harrison and 5 State of Mississippi, have invented certain new and useful Improvements in Journal-Boxes or Attachments Therefor, of which the following is a specification, reference being had therein to the accompanying drawing. 10

This invention relates in general to improvements in journal boxes, more especially the provision of what may be termed a hub plate constituting an attachment adapted to 15 be secured to the end of the journal box to receive the thrust and wear and take up undue play, as for example between the journal box and a wheel hub, although the attachment is capable of employment in connection with similar arrangements or devices. 20

A convenient embodiment of the invention comprises a plate of the character designated provided with ribs or projections adapted to 25 have slidable connection with complementary grooves or recesses on the journal box for connecting the plate to the journal box, said connection preferably being of a character to retain the plate in the desired position in reference to the box and wheel hub, 30 although the invention also contemplates still other means for securing the plate against displacement or accidental removal from the box.

35 The above referred to embodiment of the invention is illustrated in the accompanying drawings forming part hereof and the details will be apparent from an inspection of said drawings in connection with the specific 40 description hereinafter contained.

In the drawing: Figure 1 is a side elevation of a car axle journal box with the hub plate attached thereto and showing the relation of the same to a wheel, Fig. 2 is an end 45 view looking toward the hub plate as applied to a journal-box with a removable collar, the axle or journal being shown in section. Fig. 3 is an elevation of the opposite side of the hub plate detached, and, Fig. 4 is a fragmentary plan view of Fig. 1.

50 Referring more specifically to the drawings wherein like reference characters designate corresponding parts in the several views, A represents a journal box of any ordinary or preferred construction, B the wheel and C the journal or axle therefor.

The inner end or face of the journal box is provided with a pair of downwardly tapering grooves or ways D of approximately dove-tail cross section arranged near the opposite edges of the box. 60

E is the hub or wear plate composed of any suitable material for example, brass, the same being approximately U-shape, open at its bottom to accommodate the journal C, 65 and of an area and shape to constitute a broad flat bearing for the wheel hub, it being observed that the plate is of substantially the same height and width as the journal box. On that face of the plate which adjoins the end of the box I form a pair of tapering or wedge-shaped ribs F, approximately dove-tail in cross section adapted to be slid downwardly into binding engagement with the complementary side walls of 75 the grooves or ways D in the journal box which will ordinarily suffice in retaining the hub plate in place. To however provide the additional security of a lock for positively preventing accidental displacement or removal of the hub plate I provide the lower opposite ends thereof with outwardly projecting flanges G, perforated at g, adapted to overlie the adjacent side walls of the journal box to receive a pin or bolt G' passed through 80 said flanges and through the walls of the box to removably secure these parts together. The top of the hub plate is formed with an oil cell J opening through ducts j to the face of the plate as shown. The wall of the cell 85 which faces the wheel is provided with an opening K for the introduction of any suitable tool designed to remove the plate, as when the same becomes worn and a new one is to be substituted therefor. L is a 90 channel across the inner edge of the plate through which oil may pass to the journal or into which oil may flow from the journal. 95

While I have herein disclosed one specific embodiment of the invention, it will be apparent to those skilled in the art that the invention is capable of embodiment in other forms and devices. 100

I claim:—

1. In combination with a journal box, 105 provided with independent vertical dove-tail ways in the rear end thereof near its opposite edges, said ways opening at the top of said box and extending downwardly therefrom and being tapered inwardly from the 110 tops to the bottoms thereof, a wear plate provided with tapered dove tail projecting

ribs, the projecting portions interlocking with their respective ways independently of each other at the upper and lower portions of the wear plate.

- 5 2. In combination with a journal box, a wear plate adapted to overlie the rear end thereof, one of said members being provided with independent vertical recessed ways therein having undercut side walls and tapered inwardly from the tops to the bottoms thereof, and the other of said members being provided with separated tapered pro-

jecting ribs having undercut side walls adapted to slide in said ways, the projecting ribs interlocking with their respective ways independently of each other at the upper and lower portions of the wear plate. 15

In testimony whereof I affix my signature in presence of two witnesses.

CHRISTIAN WILHELMSEN.
